(57) **CLAIM**

The ornamental design for a display screen with graphical user interface as shown and described.

DESCRIPTION

FIG. 1 is a front view of a display screen with graphical user interface showing our new design;

FIG. 2 is a front view of a display screen with graphical user interface showing an alternative embodiment of our new design; and,

FIG. 3 is a front view of a display screen with graphical user interface showing another alternative embodiment of our new design.

The peripheral broken line represents a boundary of the display screen and forms no part of the claimed design. The broken lines depicting the alphanumeric characters form no part of the claimed design.
